UNITED STATES PATENT OFFICE.

JOHN W. JONES, OF UTICA, NEW YORK.

CLOTH-BOARD MACHINE.

SPECIFICATION forming part of Letters Patent No. 433,626, dated August 5, 1890.

Application filed August 26, 1887. Renewed January 15, 1890. Serial No. 336,972. (No model.)

To all whom it may concern:

Be it known that I, JOHN W. JONES, of the city of Utica, in the county of Oneida and State of New York, have invented certain new and useful Improvements in Cloth-Board Machines; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to an improved machine for the manufacture of cloth-boards; and it consists in the mechanism hereinafter pointed out, described, and claimed.

In the accompanying drawings, Figure 1 represents a side elevation of my machine. Fig. 2 represents a plan view of the same; and Fig. 3 represents a transverse section of same on line A A, Fig. 1, the parts shown in Fig. 3 lying to the left hand of line A A, Fig. 1. Figs. 4, 6, and 8 represent plan views of the boards produced upon the machine and which are introduced in order to explain the operation of the machine. Fig. 5 represents a transverse section of Fig. 4 on line B B. Fig. 7 represents a transverse section of Fig. 6 on line C C. Fig. 9 represents a transverse section of Fig. 8 on line D D, and Fig. 10 represents a transverse section of Fig. 8 on line E E. Fig. 11 represents a front elevation of the saw and a portion of the attached arbor or shaft, and Fig. 12 shows a side elevation of the same. Fig. 13 represents an end elevation of the rotary cutter I employ, and Fig. 14 represents a side elevation of a portion of the same.

Like figures of reference refer to like parts in the several figures presented.

Having described my machine in relation to the drawings, I will now proceed to describe its construction.

I provide a suitable bed or table 1, Figs. 1 and 2, having attached to and projecting downwardly therefrom suitable legs 2, Fig. 1. There are two sets of legs—one on each side of the machine—but one set being shown in the drawings. These legs are braced in

any suitable manner, so as to render the machine firm and stable. In the construction shown girts 3, Fig. 1, are used to bind or tie the legs together, and in or upon them are formed bearings 4, Fig. 1, for the reception and retention of main shaft 5 of the machine. This shaft is free to rotate in its bearings, and power for operating the machine is applied to it in any suitable manner. Mounted upon shaft 5 and rigidly connected therewith by keys, set-screws, or any other known method is pulley 6, Fig. 1, which carries the belt that connects it with the other pulleys of the machine.

Mounted upon the bed or top of the table 65 and properly fastened thereto I provide a metallic bed or frame 7, Figs. 1, 2, and 3. This bed or frame carries the various arbors or spindles upon which are mounted the saw, the rotary cutters, and other parts that are 70 hereinafter described, and is constructed substantially as follows: It consists, primarily, of a rectangular bed or frame having upwardly-projecting walls or flanges 8 on its edges, the inner opposing faces of which are 75 beveled, as shown at 9, Fig. 3. Rigidly attached to the bed at or near its center are the double journal-boxes 10, Figs. 1 and 2, in which is mounted in such manner as to admit of a free rotation the arbor or shaft 11, 80 which carries the circular saw 12.

Reference to Figs. 1 and 2 will show that I also provide two other double journal-boxes 13 13. These are gibbed or fitted into and between the beveled walls 9 of the bed in such 85 manner as to prevent their lateral vibration or play and still permit them to move horizontally either to or from the center. This movement is accomplished through the medium of the adjusting-screws 14, Figs. 1 and 2. 90 These screws are squared at their outer ends, as shown at 15, to admit the use of a wrench for rotating them. The movable journal-boxes 13 are each provided with a downwardly-projecting lug 16, Fig. 1. These lugs are perforated for the reception of screws 14. The ends of screw 14 are reduced in size where they enter lug 16, which forms a shoulder, which opposes one end of the lug. The reduced portions of the ends of the screws are 100

sufficiently long to project through the lugs far enough to receive a collar and pin, as shown at 17, Fig. 1. The screws are thus free to rotate in the lugs, but not to move laterally 5 therein. Projecting upwardly from the bed of the machine, to which they are rigidly attached, I provide lugs 18, Fig. 1. These are perforated and screw-threaded on their interior to fit the corresponding screw-threads 10 upon adjusting-screw 14. It will be readily seen that rotation of the adjusting-screws 14 will cause journal-boxes 13 to move either toward or from the center of the machine, depending upon the direction of the rotation of 15 the adjustment-screws. Journaled in each of the movable boxes in such manner as to be free to rotate therein I provide appropriate spindles or arbors for the reception of rotary cutters 19, Figs. 1 and 2. The right-hand one 20 of these rotary cutters projects from the machine to a line substantially flush with the saw, and the left-hand cutter projects to a line substantially flush with the line of the inner face of the saw. The preceding cutter—the one on 25 the right—is intended to cut the slot 44 in the material for the passage of the shaft on which the recessing-saw is mounted, and also for the reception for a spring or elastic, and the succeeding cutter—the one to the left—is intended 30 to enlarge or trim the slot made by the preceding cutter. Mounted upon each of these arbors, together with the central one that carries the saw and rigidly connected therewith, I provide flanged pulleys 20, Figs. 35 1, 2, and 3. As the plane of movement of the adjustable boxes is tangent to the periphery of pulley 6, it follows that any movement of the adjustable boxes must result in a change in the length of the belt that connects them 40 with pulley 6.

To compensate for the changing lengths of belt required, I provide the following mechanism: Hinged to the bed of the machine by lugs 21 and rod 22, Figs. 1 and 2, I provide 45 the bifurcated curved arm 23, Figs. 1, 2, and 3, having journaled in it in such manner as to freely rotate the flanged pulley 24, Figs. 1, 2, and 3. The end of arm opposite to the hinge and beyond pulley 24 is contracted and 50 brought together, and the outer end of it formed into a handle, as shown at 25, Fig. 1. Projecting upwardly from the bed of the machine I provide a curved slotted sword piece or guide 26, Fig. 1. The bifurcated arm contacts with one side of the guide and is connected therewith by the thumb-nut and bolt 55 27, Figs. 1 and 2. The arm is perforated for the reception of shank of bolt 27, while the other end projects through the slot in the guide far enough to receive the thumb-nut. The arm can be moved into any desired position and held there by tightening the thumb-nut. Belt 28, Fig. 1, partially encircles and 60 enwraps the whole system of pulleys. Consequently any variation in length of belt required, due to the movement of the movable

boxes and their attached arbors and pulleys, can be compensated for by varying the location of the arm 23 and its attached pulley 24.

In order to successfully operate my machine, it is necessary to provide some means by which the boards to be operated upon can be retained in certain definite positions relative to the saw and the rotary cutters. To accomplish this end, I provide the following 70 mechanism: The edge of the bed next to the saw and rotary cutters is recessed, as shown at 29, Fig. 3, to admit of the reception of the slotted uprights 30, Figs. 1, 2, and 3, and permit their free vertical movement therein. 80 These slotted uprights are tied or bound together near their upper end by the tie or girt 31, Figs. 1 and 3. This tie or girt is adjustable vertically upon the slotted uprights, and is held in any desired position therein by the 85 thumb-nuts and bolts 33, Figs. 1 and 2. (Not shown in Fig. 3.) It will be noticed by reference to Fig. 1 that I employ a screw 34 for elevating or lowering the L-shaped tie or girt 32, which acts as a guide for the material fed 90 to the machine or upon which the machine operates. The girt 32 is properly perforated and screw-threaded for the reception of the adjusting-screw 34. The upper end of this screw is reduced in size and inserted into a 95 proper perforation in lug 35, which is attached to and projects from the bed of the machine. (Not shown in Figs. 2 and 3.) The reduced end of screw 34 is sufficiently long to project 100 through the lug far enough to receive an ordinary collar and pin, which admits of the rotation of the screw, but does not admit of its vertical movement. The screw is provided at its lower end with a thumb-nut or equivalent device to facilitate its manipulation. 105

It will be observed that when the L-shaped girt 32 is, by means of the thumb-nut 33, clamped to the uprights 30, rotation of the screw 34 will result in either raising or lowering the connected parts, depending upon 110 the direction in which the screw is rotated.

Reference to Figs. 11 and 12 will show the construction of the saw I use in my machine, and which, so far as I am aware, is new and novel as respects its combination and attachment to and with the arbor or spindle upon 115 which it revolves.

Heretofore, so far as I have been able to ascertain, it has been the general custom in attaching a saw to its arbor to superimpose the saw between collars, which, in common with the saw, were perforated to admit of the insertion of the arbor. This construction necessitated the use of a nut or equivalent device to tighten the collars and clamp the 120 saw between them. Other devices have been in limited use; but none of them, so far as I am informed, have attained the ends sought and accomplished in my invention—viz., a 125 saw, one side of which is a perfectly plane surface with no projection of any kind thereon. 35, Figs. 11 and 12, shows an ordinary

circular saw. This I attach to its arbor 36 in such manner that one of the sides of the saw shall be a perfectly plane surface. Various modes of attachment can be utilized. The 5 saw may be perforated and the outer edges of the perforation countersunk, so that the end of the arbor may be riveted down flush with its surface, or it may be screwed onto the arbor. Various other means would readily 10 suggest themselves to one skilled in the art. As it is not desirable to remove the saw from its arbor after being once attached thereto, I preferably construct arbor 36 of such form and size that it may be inserted into a proper 15 orifice in the end of the main arbor or spindle of the machine, as shown at 37, Fig. 2, and be held therein by set-screws, ordinary taper fit, or any other known means. A variety of sizes of saws can be kept in stock and used 20 as occasion requires.

The rotary cutters employed by me are represented in Figs. 13 and 14, which are respectively end and side views of the same. They consist, essentially, of a cylinder of 25 steel, having lateral longitudinal depressions, the edges of which form cutting-edges, as shown at 38, Figs. 13 and 14. The cutters are properly designed and constructed to fit orifices in the main arbors of the machine, as 30 shown at 39, Fig. 2, and are held therein by any suitable means. I do not, however, limit myself to the particular style or shape of cutter shown, as various other shapes or style could be made to answer the same purpose.

35 In describing the operation of my machine it will be necessary to refer to Figs. 4, 5, 6, 7, 8, 9, and 10, which show the nature of the operation performed by it. The boards represented in the figures are cut to proper 40 length and their ends rounded, when the balance of the operations are performed on the machine. Each board is provided with a central longitudinal recess or pocket 40 for the reception of a tag or label 41. This tag 45 or label has connected to it near one end one end of the coiled spring or its equivalent 42. The other end of the coiled spring is connected with the board at 43. The spring lies in the slot that forms a communication 50 between the central pocket 40 and the outside of the boards. This construction allows the tag 41 to be withdrawn from the pocket 40, examined, and then automatically retracted into the pocket by the action of the 55 coiled spring. The function of my machine is to cut or form the pockets of the slot described. The boards are set upon their edge upon the L-shaped guide or girt 32, Figs. 1, 2, and 3, and their inner and upper faces 60 held against the girt 31, Figs. 1 and 3. They are then passed from right to left along and across the face of the machine. They first come in contact with the right-hand rotating cutter 19, which cuts the slot 44, Figs. 8, 9, 65 and 10. The movement of the board being continued it next contacts with circular saw

12, Figs. 1, 2, and 3, which cuts the pocket or recess 40, Figs. 4, 5, 6, 7, 8, 9, and 10. Passing still farther along the board contacts the left-hand rotating cutter 19, which enlarges 70 the slot 44, as shown at 45, Figs. 4, 5, 6, and 7. To limit the longitudinal movement of the board, I employ movable stop 46, Figs. 1 and 2, which can be moved along girt 32 to any desired position and held there by cross-headed screw 47. For holding the board against the side of the girt I employ flat spring 48, Figs. 1, 2, and 3, which contacts the side of the board and holds the same firmly against the girt. In the foregoing 80 operations it is assumed that the saw and rotary cutters are revolving at a sufficient speed to accomplish the processes described.

Various sizes and combinations of cutters and saw can be employed to produce a great 85 variety of results; hence I do not limit myself to the specific styles of cutters and products herein described. The spindles carrying the rotary cutters being adjustable laterally, and the girts and attached parts that 90 form guides for the work while the same is in process being vertically adjustable, it follows that great variety of work can be produced upon my machine.

It is obvious that various changes in the 95 structure and conformation of my machine could be made without departure from the spirit or central feature of my invention, which is the employment, in combination with rotary cutters, of a circular saw having one of 100 its sides a perfectly plane surface; hence I do not limit or confine myself to the precise specific construction, combination, and conformation of parts herein set forth and described.

What I claim as new, and desire to secure 105 by Letters Patent, is—

1. In a cloth-board machine, the combination of a recessing saw or cutter mounted upon the free end of a shaft, and a preceding 110 cutter of a smaller diameter and of a diameter as great as the shaft of the recessing-cutter adjacent thereto, mounted upon the free end of a shaft in advance of and projecting to the plane of rotation of the recessing-cutter.

2. In a cloth-board machine, the combination of the recessing saw or cutter mounted upon the free end of a shaft, and a preceding 120 cutter of a smaller diameter and of a diameter as great as the shaft of the recessing-cutter adjacent thereto for cutting a slot in the material for the passage of the shaft of the recessing-cutter and for the reception of a spring or elastic, the cutter being mounted 125 on the free end of a shaft in advance of and projecting from the shaft side of the recessing-cutters to the plane of rotation of the recessing-cutter, the two cutters being mounted upon substantially parallel shafts mounted 130 in a frame, and an adjustable gage or guide for directing the material to be operated upon

at equal distance from the centers of each cutter.

3. The combination of a circular saw for recessing the material, mounted on the free end of a shaft, the rotary cutter for cutting a slot for the passage of the saw-shaft and reception of a spring or an elastic, mounted upon a shaft in advance of and substantially parallel with the saw-shaft and projecting

from the machine to a line in a plane substantially with the inner face of the saw.

In witness whereof I have affixed my signature in presence of two witnesses.

JOHN W. JONES.
